UNITED STATES PATENT OFFICE.

JOHN SELLERS BANCROFT, OF PHILADELPHIA, PENNSYLVANIA, ASSIGNOR,
BY MESNE ASSIGNMENTS, TO LANSTON MONOTYPE MACHINE COMPANY,
OF WASHINGTON, DISTRICT OF COLUMBIA, A CORPORATION OF VIR-
GINIA.

RECORD-STRIP-FEEDING MECHANISM OF AUTOMATIC TYPE-CASTING OR OTHER MACHINES.

SPECIFICATION forming part of Letters Patent No. 700,291, dated May 20, 1902.

Application filed December 3, 1901. Serial No. 84,543. (No model.)

To all whom it may concern:

Be it known that I, JOHN SELLERS BANCROFT, residing at Philadelphia, in the county of Philadelphia, State of Pennsylvania, have **5** invented certain new and useful Improvements in the Record-Strip-Feeding Mechanism of Automatic Type-Casting or other Machines; and I hereby declare the following to be a full, clear, and exact description of **10** the same, reference being had to the accompanying drawings, forming a part of this specification, and to the figures of reference marked thereon.

This invention relates to improvements in **15** or pertaining to the record-strip-feeding mechanism of automatic type-casting and other machines, and has for its object to provide a paper-holder competent to present and maintain the strip in proper relation to the feeding devices and air-ports and at the same time adapted to be readily applied to or removed from the strip to facilitate the insertion, removal, or readjustment of the latter.

To this end the invention consists in the **25** employment of two bars or rollers, one on each side of the cross-bar, freely suspended, so as to gravitate toward said cross-bar and engage the strip on opposite sides thereof intermediate the supply and winding spools to **30** hold the strip flat and in proper relation to the cross-bar and feeding devices, and in connecting the supports of said bars or rollers to the air-bar in such manner that the elevation of the latter to uncover the strip will automatically effect a withdrawal of said bars or rollers, thereby facilitating the insertion or removal of the record-strip.

A preferred embodiment of the invention will first be described, and the novel features **40** thereof pointed out in the claims.

In the accompanying drawings, Figure 1 is a front elevation, and Fig. 2 a vertical section, of a portion of the paper-feed with the improvements applied thereto. Fig. 3 is a **45** vertical section showing the effect of elevating the air-bar. Fig. 4 is a view in perspective of the roll-hanger complete, the rolls being omitted. Fig. 5 is a detail view showing

the manner of effecting the connection between the hangers. **50**

Similar figures in the several views denote like parts.

The paper-feed mechanism with which the improvements are shown associated is that of Patent No. 674,362. 1 designates the **55** frame; 2, the cross-bar containing the air-ports; 3, the air-bar pivoted on shaft 4; 5, the sleeve on said shaft-carrying arms 6; 7, the connecting-rods between arms 6 and the air-bar; 8, the compression-springs interposed **60** between the air-bar and arms 6, and 9 the driving-link detachably connected to one of the arms 6.

The record-strip is drawn over the cross-bar by the pin-wheel-feeding devices, the latter acting to intermittently advance the strip while the air-bar is elevated and to hold the strip stationary, with the signals or perforations in line with the ports, while the air-bar is in its lowered position. The strip is drawn **70** from a supply-spool on one side of the cross-bar and delivered to a winding-spool on the other.

It is essential that the record-strip be so **75** adjusted relatively to its feeding devices that the signals or perforations will register with the series of air-ports or other controlling devices when the strip is at rest and that this relation shall be preserved during successive feed movements, and in order that this **80** adjustment may be readily and quickly performed, as well as to facilitate the insertion and removal of the strip and the shifting from one section thereof to another, the feed-wheels are mounted to project their pins radially beyond the surface of the cross-bar, and the air-bar is arranged so that it can be **85** swung back from the cross-bar to uncover the latter, thereby affording ample opportunity for the placing of the strip in proper relation to the feeding devices. The facilities thus afforded for manipulating the record-strip would be ample for the purpose if the material employed was of uniform texture, so that it would retain its original dimensions and **90** lie perfectly flat upon the cross-bar and pin-

wheels; but experience has demonstrated that it is impracticable to procure paper suitable for the purpose which will not under the conditions of use develop at different and irregular intervals slight variations in dimensions, resulting in wrinkles or unequal extension or contraction of the margins.

The tension on the strip as developed between the supply and winding spools is substantially uniform in amount, but is unequally distributed owing to these variations in dimensions throughout different portions of the material, with the result that at times one margin will be held tightly in contact with the cross-bar or pin-wheel, while the opposite margin is so loose that it may escape from the control of the pin-wheel on that side, thereby destroying registry. To meet and overcome this defect is the primary object of the present improvement.

Upon opposite sides of the cross-bar or support 2 and extending longitudinally thereof are arranged two rods or rollers 10 11 for engaging the record-strip intermediate the cross-bar and the supply and winding spool, respectively. Each roller is supported in an independent hanger 12 13, pivotally supported in a manner to cause its roller to gravitate toward the record-strip, thus serving not alone as a supplemental tension device, but also as a floating tension to hold the section of the strip lying between the rollers in close contact with the peripheries of the pin-wheels, thus insuring the entrance and engagement of the pins in the marginal feed perforations of the strip.

In the preferred form of embodiment shown the hangers 12 13 each comprise two plates or frames independently pivoted at their upper ends upon a rod 14, the latter located above and intermediate the vertical walls of the cross-bar.

Each roll is provided with two circumferential grooves 15, and the hangers are formed with elongated bearings 16, open on one side for the reception of the rolls and provided with offsets 17, coöperating with the circumference of the rolls to retain them in position. By this means each roll is supported in a manner to cause it to gravitate toward one side of the cross-bar and at the same time is free to yield laterally at either or both ends in a direction perpendicular to the plane of the record-strip, thus insuring equal action across the latter and holding it in proper relation to the cross-bar and feeding devices.

To automatically effect the withdrawal of the rollers from the cross-bar when the air-bar is withdrawn or thrown back, as seen in Fig. 3, as well as to adapt the attachment to existing machines, the rod 14, upon which the hangers are pivoted, is attached to ears 18, formed on horizontal extensions 19 of a plate 20. This plate 20 forms the base of the attachment, and it is detachably secured to the air-bar and its connections, as by curving

the rear portion to partially embrace sleeve 5, while the horizontal extensions 19 are perforated for the reception and passage of connecting-rods 7. The compression-springs 8 bear against plate 20 and retain it in position, so that it will follow the motions of the air-bar, and when the latter is elevated, as in Fig. 3, to uncover the cross-bar and feed-wheels it will engage and elevate the front 75 hangers 13.

To the side pieces of frame 1 and on an axis 24 eccentric to that of the air-bar are pivotally attached the inner ends of two links 21, whose outer or opposite ends are connected 80 to a rod 22. A single link 21 might answer the purpose, but two are preferred, as insuring greater stability and uniformity in action. This rod 22 projects through openings 23 in the rear hanger 12, said openings being to one 85 side of rod 14 and enough larger than rod 22 to permit the requisite limited movements of hanger 12 when dependent with its roller operating upon the record-strip. By reason of the difference in the centers about which 90 rods 14 and 22 are compelled to turn when the air-bar is swung back rod 22 by its engagement with hangers 12 will cause the latter to also swing outward and away from the cross-bar and feed-wheels, thereby completely uncovering those members and affording free access thereto. Thus the lifting of the air-bar not only removes the pressure of rollers 10 11 from the strip, but it automatically effects their withdrawal to a point 95 where they will not interfere with the placing or removal of the record-strip.

Having thus described my invention, what I claim as new, and desire to secure by Letters Patent, is—

1. In a record-strip-feeding mechanism the combination with the cross-bar, pin-wheels and air-bar, of two tension-rollers, the one in front and the other in rear of the cross-bar and both gravitating toward said cross-bar; substantially as described.

2. In a record-strip-feeding mechanism the combination with the cross-bar, feed-wheels and air-bar, of two tension-rollers, one in front and the other in rear of the cross-bar, 115 said rollers being supported to gravitate toward the cross-bar at points below the axis of the feed-wheels; substantially as described.

3. In a record-strip-feeding mechanism the combination with the cross-bar, feed-wheels 120 and movable air-bar, of two gravitating tension-rolls located on opposite sides of the cross-bar and supported so as to permit lateral displacement of either or both ends under the action of the record-strip, substantially as described.

4. In a record-strip-feeding mechanism the combination with the cross-bar, feed-wheels and pivoted air-bar, of tension-rolls for engaging the record-strip on opposite sides of 130 the feed wheels and devices intermediate said air-bar and tension-rolls for automatically

withdrawing the latter to uncover the record-strip upon the withdrawal or throwing back of the air-bar, substantially as described.

5. In a record-strip-feeding mechanism the combination with the feeding devices and cross-bar and the air-bar movable toward and from the latter, of two hangers pivotally mounted upon the air-bar and each supporting a roller in position to engage the record-strip on one side of the feeding devices; substantially as described.

6. In a record-strip-feeding mechanism the combination with the pivoted air-bar, of two supplemental tension-rolls and hangers for said rolls each comprising two independent supporting-plates separately and meditately pivoted upon the air-bar, to permit lateral displacement of each roll at either end thereof; substantially as described.

20 7. In a record-strip-feeding mechanism the combination with the cross-bar feed-wheels and laterally-movable air-bar, of floating or supplemental tension-rolls each loosely journaled in a hanger pivotally connected to the air-bar at a point intermediate the front and rear walls of the air-bar, whereby said rolls are caused to approach by gravity to exert pressure upon the record-strip and to yield laterally at either end, substantially as de-25 scribed.

30 8. In a record-strip-feed mechanism the combination with the pivoted air-bar, of a plate detachably applied thereto, a rod supported on said plate, a dependent hanger pivotally attached to said rod at a point to one side of the axis of the air-bar, a roll mounted in said hanger, and a link or links pivotally

connected to the frame and hanger and operating to swing the latter upon its supporting-rod as the air-bar is withdrawn from the cross-bar; substantially as described. 40

9. In a record-strip-feeding mechanism the combination of the following elements, to wit: a cross-bar; feed-wheels; a pivoted air-bar; two hangers, each carrying a tension-roll, dependent from and pivotally attached to the air-bar, one of said hangers extending over the air-bar in position to be engaged by the latter when moved away from the cross-bar; and a link or links connecting the opposite 45 hanger to the frame in a manner to cause its elevation when the air-bar is retracted; substantially as described. 50

10. As a new article of manufacture a supplemental tension attachment for record-strip-feeding mechanism such as described, the same comprising a bed-plate or frame adapted for attachment to a pivoted air-bar on its supports; a rod mounted on said frame; two hangers pivotally suspended from said 55 rod and each comprising two independent plates provided with open bearings for the reception of a roll; a rod engaging enlarged openings in the plates constituting one of said hangers; links engaging said last-named 60 rod; and another rod engaging said links and adapted to engage bearings on the frame forming the support for the air-bar to which the attachment is to be applied; substantially as described. 65
